COUNTERBALANCED SHAKER CONVEYER

Jean Sabes, Anzin, France, assignor to Jaruza,
Zurich, Switzerland, a corporate body of Switzerland

Application July 23, 1948, Serial No. 40,294
In Belgium February 6, 1948

2 Claims. (Cl. 198—14)

1

It has already been proposed to construct apparatus which are intended to pick up and discharge materials in heaps. Some of them are very bulky, heavy and difficult or complicated to manipulate. Others make use of a pick up member which is given a vibratory movement of great frequency and small amplitude (800 vibrations per minute for a movement of a few millimetres, for example). This movement is produced by unbalanced arrangements or the like.

These latter apparatus in particular have the serious drawback of becoming "limp" when the oscillating member comes up against blocks, engages a compact material or when the shovel is too heavily loaded, that is to say that in these cases, the amplitude of the vibrations decreases owing to the difficulty of the work, up to the point of stopping the apparatus.

Furthermore, since for all these apparatus the discharge of the materials picked up is only effected in one direction, generally in the direction of the longitudinal axis, it is often difficult to adapt the apparatus suitably to an existing general organization for the removal of materials from a yard or from a mine level.

The present invention has for its object an apparatus for picking up and discharging materials by means of a vibrating chute, which can be used for all materials in heaps and in all yards, storage dumps, or mine levels. The apparatus can furthermore be adapted to effect stopping and loading.

The apparatus according to the invention comprises a chute terminating in a shovel, and the body of which is positively set in vibration, the reaction of these vibrations on the frame of the apparatus being neutralized by the vibrations in opposite phase of a body having a mass equivalent to the first one. It is thus possible to lighten considerably the frame of the apparatus.

The equivalent mass may be formed by a portion of the chute itself, in which case said chute is divided along its length into two portions of equal masses.

It is also possible to use an independent balancing mass which may be provided with engaging tools for disintegrating the material to be picked up. In this case, the apparatus is suitable for working in a level, for example for directly boring the rock of said level.

The frame of the apparatus may be supported by wheels, endless tracks or skids and said apparatus may be self-powered or connected to a source of power.

2

Since the vibrating chute effects the horizontal movement and the lifting of the material, the same may be taken up directly at the outlet of said chute by a preferably continuous conveyor.

5 The problem of mechanical picking up as a whole is thus solved by:

An action which prepares the material for picking up,

10 An assembly of simple and rugged members for the picking up operation proper,

A device of great flexibility of installation and working for discharging the material picked up.

15 The connection of the apparatus to the general device for removing materials from the yard or from mine levels (conveyor belts, oscillating chutes, wagons, movable elevators, etc.) is preferably effected by means of an intermediate

20 conveyor such as a loading device with chains or belts. Said intermediate conveyor may advantageously be pivotally connected by one of its ends to the rear portion of the apparatus and by the other end to a carriage which may carry the control station of the apparatus and of the conveyor. These pivotal connections enable very numerous relative orientations to be obtained, whereby the apparatus can be fitted to any system for discharging materials.

The ensuing description made with reference 30 to the accompanying drawing which is given by way of a non-limitative example, will make it clearly understood how the invention can be carried out, the peculiarities which become apparent both from the drawing and from the text forming, of course, part of said invention.

Figs. 1 and 2 respectively show an elevational and a plan view of an apparatus according to the invention.

Figs. 3 and 4 respectively show an elevational 40 and a plan view of an apparatus of this type, connected to a continuous conveyor, operating in a level.

Fig. 5 is a diagrammatic plan of the apparatus for Figs. 1 and 2.

45 Figs. 6 and 7 show the outer ends of the buffers. Fig. 8 shows a detail of the invention.

In the central portion of the apparatus shown in Figs. 1 and 2 and extending along the whole length thereof is mounted a vibrating chute 1 which is slightly inclined with respect to the horizontal. The front end 2 which engages the material to be picked up widens out in the shape of a shovel, the rear end 3, which is cut away into a quarter circle, forms a discharge lip; the 50 bottom 4 is provided with projections 5 which

55

are suitably shaped and distributed to facilitate the feed of the material.

Two links 6 near the front and two others 7 near the rear are pivotally connected, on the one hand to the frame 8, on the other hand to the vibrating chute, and ensure the suspension of said chute.

The suspension links 6 and 7 form a well-defined angle with the slope of the chute so as to insure the feeding of the material owing to the vertical vibratory component action, thus avoiding complicated mechanisms currently used for driving vibrating chutes which operate through the effect of the variations of the acceleration between the to-and-fro strokes.

Two horizontal connecting rods 9, the small ends of which are pivotally connected to the vibrating chute, have their big ends mounted on a crankshaft 10: said crankshaft transmits the vibratory movement to the chute 1 by a direct and positive mechanical action.

The rotation of the crankshaft 10 is obtained by means of two gear trains, one a spur-gear train 11, the other a bevel-gear train 12, which are driven by a motor 13 provided with a fly-wheel 14, the mass of which enables the apparatus to overcome the momentary difficulties of its operation which are due to the load of the shovel for example.

The balancing of the oscillations of the chute 1 is effected by the masses of two counterweights 15 which are arch-shaped and to the front ends of which are keyed two buffers 16 terminating in domed or pyramidal surfaces 17 or surfaces which are deflected from their axes, if desired with pointed or sharp bits according to the purpose for which the apparatus is intended and the nature of the material to be picked up.

Two links 18, and two other links 19, which are pivotally connected on the one hand to the frame 8 and on the other hand to the counterweights 15, provide the suspension for said counterweights.

Two horizontal connecting rods 20, the small ends of which are pivotally connected to the counterweights 15 have their big ends mounted on the crankshaft 10; said crankshaft transmits the vibratory movement to the counterweights 15 by a direct and positive mechanical action. The mounting of the links 9 and 20 in phase opposition effects the balancing of the two vibratory movements. Thus the counterweight which is necessary for balancing the chute is used for assisting in the work of cutting the material.

All the oscillating mechanism may be mounted on a translatory member of any type: endless track, wheels, etc. Figs. 1, 2, 3, 4 show a frame 8 supported by two identical endless track carriages 21, one on the right, the other on the left of the apparatus. Each of said carriages is adapted to transmit to the endless track 22 the necessary movement for propelling it by the action of a suitably chosen motor 23 by means of a bevel gear and worm transmission 23a.

The frame 8 is connected to each of the carriages 21 by the rear horizontal spindle 24 of the rollers of the endless tracks and by two small hydraulic jacks 25, the stroke of which is used for adjusting the height of the shovel 2 of the oscillating chute relatively to the ground.

Finally, stone deflectors 39, supported by the frame 8, clear the way in front of the wheels or the endless tracks.

It is easy to see that in this apparatus, a preparatory action to the picking up by the shovel 2

is obtained by a regular hammering of the material to be picked up, by means of the two buffers 16 which disintegrate the compressed portions, cause the elements of a granular and stony material to roll towards the apparatus, and break up the pieces which are too large to be picked up in one piece. The apparatus is therefore suitable for all sizes of grains, either separated or mixed.

The positive mechanical control of the vibrating chute produces, independently of all the reactions of the material to be picked up, oscillations of which the frequency may be between 500 and 1,000 vibrations per minute, and the amplitude may reach 25 millimetres. The simplicity of the mechanical members, their efficient protection, enables the apparatus to be used in all yards and storing premises; furthermore, its small height makes it perfectly suitable for picking up materials in mine levels.

An example of such a use is shown in Figs. 3 and 4.

The material which is picked up by the shovel 2 of the chute 1 is poured from the end 3 into a cup 27 forming the foot of a loading device 28 and a pivot 29 which is common to the apparatus 26 and the loading device 28 enables the angle 30 to be given all values from 0° to about 120°.

In the case of Figs. 3 and 4, the loading device 28 is a flat chain loading device; it lifts the material above the discharge member 31 and projects it thereon by gravity.

The upper end of the loading device bears against a movable carriage 32 with three wheels, two steering wheels 33 and one driving wheel 34 which is driven by the motor 35 located next to the control cabin 36.

The loading device 28 and the carriage 32 are assembled to one another by means of the pivot 37, enabling a very great latitude of variation to be given to the angle 38.

The loading device 28 which is connected to the pick up device may also rest on two skids adapted to slide along the ground, its position relatively to the pick up device being determined and retained by a stay which enables the angle between the axis of the loading device and the axis of the pick up device to be varied, or by a cable adapted to wind on a winch mounted on said loading device.

When the loading device 28 is supported at one of its ends by the carriage 32, the movement of its chain or of its belt can be transmitted from the carriage 32 by means of a vertical shaft which is driven by the motor of said carriage and which is provided at the end with a male fitting adapted to engage in a female socket of the same shape, thereby enabling the necessary power for the conveyor to be obtained from the carriage 32 and a light intermediate conveyor to be provided.

An illuminating device by means of floodlights may be provided for using the apparatus in mine levels or night work in storage dumps.

The controls for the various driving means (electricity, compressed air, pressure water, etc.) which effect the operations for picking up the material, propelling the pick up device, raising the loading device, and driving the three-wheeled carriage, are centralized near the driver's hands, who is located at 36.

In the case in which the apparatus is merely intended to be a loading apparatus and consequently very light, the balancing counterweights 15 may be eliminated and the chute divided into two successive sections of equal masses, said sections being controlled by the two op-

positely located crank-pins of the crankshaft, which themselves vibrate in opposite directions and balance one another. The frame may be mounted on skids or on wheels which can be orientated or not; in this case, the orientation of the apparatus is effected by shifting it by means of a miner's bar.

The two-element loading chute may supply either an elevator, or a conveyor that loads a stationary conveyor, or a mine-car.

It is also possible to use the apparatus directly as a cutting and loading tool in coal mines for example. In this case, the counterweights 15 which balance the vibrating chute are provided with a series of bits forming a chisel, which are located vertically above one another and which detach the coal in situ, producing a kind of vertical nicking and making the coal fall onto the vibrating loading chute.

The whole apparatus may in this case be mounted on a sledge and hauled into the face by a winch fixed to the top of the face or provided on the machine.

It is obvious that modifications of detail may be made in the apparatus which has just been described, in particular by substituting equivalent technical means, without thereby exceeding the scope of the invention as set forth in the appended claims.

What I claim is:

1. Apparatus for receiving, moving and discharging solid material in heaps, comprising, a frame, a chute movably mounted on the frame, means connected to the chute for vibrating same, counterweight means movably mounted on the frame, buffer means carried by the counterweight means for loosening the material to be received, second means connected to the counterweight means for vibrating same in phase opposition to the chute, and a member movably mounted on the frame and connected to the first named means and second means and imparting to one of the means a motion opposite in phase

to the motion imparted to the other means, whereby the vibration of the counterweight means has a phase opposite to that of the chute.

2. Apparatus for receiving, moving and discharging solid material in heaps, comprising, a frame, a pair of links pivoted at their upper ends to the frame, a second pair of links spaced from the first pair and pivoted at their upper ends to the frame, a chute pivotally supported by the lower ends of the two pairs of links, means connected to the chute for vibrating same, counterweight means movably mounted on the frame, second means connected to the counterweight means for vibrating same in phase opposition to the chute, a member movably mounted on the frame and connected to the first means and second means and imparting to one of the means a motion opposite in phase to the motion imparted to the other means, whereby the vibration of the counterweight means has a phase opposite to that of the chute and buffer means carried by the counterweight means for loosening the material to be received.

JEAN SABES.
